UNITED STATES PATENT OFFICE.

HARRY COHEN, OF PHILADELPHIA, PENNSYLVANIA.

PLATE-PUNCHING MACHINE.

1,320,206.

Specification of Letters Patent.

Patented Oct. 28, 1919.

Application filed December 27, 1918. Serial No. 268,549.

To all whom it may concern:

Be it known that I, HARRY COHEN, a citizen of the United States, residing at Philadelphia, in the county of Philadelphia and 5 State of Pennsylvania, have invented certain new and useful Improvements in Plate-Punching Machines, of which the following is a specification.

One object of my invention is to provide 10 a plate punching machine of simple and durable construction which will be operative to punch a number of holes at the same time.

Another object is to provide means operative to permit the ready insertion and removal of the plates before and after punching.

Another object is to construct my machine in such manner that certain of the parts can be readily changed so as to punch holes at 20 different distances apart.

These objects, and other advantageous ends which will be described hereinafter, I attain in the following manner, reference being had to the accompanying drawings in 25 which

Figure 1 is a front end elevation of my improved machine,

Fig. 2 is a sectional elevation of my improved machine taken on the line 2—2 of 30 Fig. 3,

Fig. 3 is a sectional plan view taken on the line 3—3 of Fig. 2; a portion of the punched plate being broken away,

Fig. 4 is a view of similar nature to that 35 of Fig. 2 showing the plate after it has been punched, stripped from the punches, and raised from the bed at an incline ready to slide out of the machine,

Fig. 5 is an enlarged fragmentary section 40 showing certain of the elements of my invention,

Fig. 6 is a fragmentary elevation showing certain of the parts of my improved machine operative to raise and hold the punched 45 plate at an incline, as illustrated in Fig. 4, and

Fig. 7 is a top plan view showing a punched plate capable of being punched by my improved machine.

50 Referring to the drawings, 8 represents the frame of my improved machine which includes two heavy metallic side walls 9 and 10 which are spaced apart and, at their top, support a bridge cover 11 which is secured 55 by bolts 12 to said walls 9 and 10. The walls 9 and 10 at their tops provide bear-

ings for the crank shaft 13 having cranks 14 and 15 thereon. The bridge cover 11 has a central pendant bearing 16 for supporting the crank shaft 13 midway between the inner surfaces 17 and 18 of the walls 9 and 10 respectively. The crank shaft 13 has a heavy gear wheel 19 secured thereto outside of the frame 8, said gear wheel being in mesh with a smaller gear wheel 20 on a 60 main driving shaft 21, said driving shaft also having a pulley 22 thereon which is rotated by a belt 23.

A heavy metallic casting or head 24 is positioned between the walls 9 and 10 and has 70 its end portions 25 and 26 slidable within slideways 27 and 28 formed in the walls 9 and 10 respectively. The head 24 has two pairs 29 and 30 of upwardly extending lugs which provide bearings for pins 31 and 32. 75 Crank arms 33 and 34, respectively, connect the cranks 14 and 15 with the pins 31 and 32. Thus, it will be seen that a rotation of the crank shaft 13 will impart a reciprocating movement of the head 24 vertically 80 within the slideways 27 and 28.

The lower surface of the head 24 has a punch casing 35 secured thereto, said punch casing being preferably made in sections 36 which are independently secured to the 85 head 24 by screws 37, which fit within tapped holes in said head 24. Any of the sections 36 is capable of supporting a punch 38 which is removably secured within said sections by set screws 39 (Fig. 5). 90

The arrangement of the punches 38, as shown in the several views of drawing, is such as to punch a plate having the arrangement of holes, as illustrated in Fig. 7. However, it will be understood that this arrangement can be changed either by removing and substituting different sections 36 in the punch casing 35 or by removing certain of the punches 38 by loosening their respective set screws 39. 95

For the purpose of convertibility, as just described, the bottom of the head 24 can be provided with extra tapped holes 40, a few of which are illustrated in Fig. 1. For example, if it is desired to set the punches four inches apart, where they have previously been punching at two inches apart, it can be readily accomplished.

A die bed 41 extends transversely between the walls 9 and 10 and at its top has a recess 42 which provides a receptacle for the plate 43 to be punched. The recess 42 provides a

ledge 44 and also provides a cavity in which are mounted the dies or die blocks 45, said dies being made in separate lengths so that they can be readily changed or replaced with dies having holes of either different diameters or holes at various distances apart. The bottom of the die bed 41 has outlet passages 46 so that the punchings can fall from the bed upon a tray 47, said tray being normally mounted on lugs 48 which are so disposed as to normally hold the tray in an inclined position, as clearly shown in Fig. 2, it being noted that when the head 24 descends the plate will be punched, the punches passing through the plate and also through the respective die holes.

Buffer plungers 49 are slidably mounted in the die bed 41 and have disk heads 50 adapted to engage the lower surface of the plate 43 when positioned between the cavity 42. The buffer plungers 49 are backed by coiled springs 51, as clearly shown in Fig. 2, said springs normally tending to move the buffer plungers upwardly.

Lifting rods 52, 53 and 54 are slidably mounted within the die bed 41, and at their upper ends have anti-friction rollers 55 thereon which are adapted to engage the lower surface of the plate 43, at certain times as will hereinafter be more thoroughly described.

Three counter shafts 56, 57 and 58 are rotatably coupled by driving belts 59 and 60. The shaft 58 extends to the outside of the frame 8 and has a sprocket wheel 61 secured thereto, said sprocket wheel 61 being pivotally connected to a sprocket wheel 62 on the outer end of the crank shaft 13 by a chain 63. In this manner, it is obvious that the shafts 56, 57 and 58 will be simultaneously rotated when the crank shaft 13 is in motion. The counter shafts 56, 57 and 58 have, respectively, secured thereto cams 64, 65 and 66. These cams, as clearly shown in Figs. 2 and 4, are adapted to engage the lower ends of the lifting rods 52, 53 and 54 and, as will be noted, the cams 64, 65 and 66 are of various sizes or "throws", and the length of their dwell surfaces 67 varies decreasingly from the cam 64 to the cam 66. Fig. 2 of the drawing shows the lifting rods in their lowermost position and the plate 43 within the cavity 42 and resting upon the buffer plungers 49, ready to be punched.

The head 24 supports depending suspension rods 68 which are slidable vertically and at their upper ends have enlargements 69 movable within chambers 70. The suspension rods 68 at their lower ends support a punch stripping plate 71 which has holes 72 through which the respective punches 38 extend. The chambers 70 are closed at their tops by plugs 73, see particularly Fig. 5. Coiled springs 74 are positioned within the chambers 70 between the tops of the en-

largements 69 and the bottoms of the plugs 73. These springs normally tend to move the suspension rods 68 downwardly and with them the stripping plate 71. This causes a relative movement between the stripping plate and the punches 38 so that if the plate 43, after being punched, attempts to raise with the punches, said relative movement between the stripping plate and the punches will cause the plate 43 to be stripped from the punches.

The front of my improved machine is provided with rollers 74^a which have their tops substantially in alignment with the top of the die bed 41. These rollers 74^a provide supporting means for the plates to be punched both during their insertion and removal. It will be further noted that the surface 75 of the die bed 41 slants downwardly, as clearly shown in Figs. 2 and 4 to facilitate the removal of the punched plate.

The operation of my improved punching machine is as follows:

The plate to be punched is placed upon the rollers 74 and slid inwardly so as to occupy the position illustrated by the plate 43 in Fig. 2. The crank shaft 13 is then started by any suitable controlling mechanism (not illustrated) and the head 24 descends until the punches 38 penetrate the plate 43 to punch the desired holes. The buffer plungers serve as intermediate supporting means to keep the portion between the punched parts in the proper plane, so that the punches strike fairly and squarely against the plane upper surface of the plate. It will be understood that it is not intended that the springs 51 take the entire pressure of the punches, for the reason that the die blocks will do this.

However, the buffer plungers keep the plate in a plane during the initial impact with the punches and thereby secure a more perfect punching of the plate. After the plate has been punched and the head 24 ascends, the stripper plate will insure the removal of the punched plate 43 from the punches. At this time the cams 64, 65 and 66 will operate in succession, first to lift one edge of the plate and then to lift the opposite edge of the plate so that the cams, when all are operating upon their lifting rods 52, will raise the plate into an inclined position, or in other words, from the position shown in Fig. 2 to the position shown in Fig. 4.

While I have described the cams 64, 65 and 66 as single cams, it will be understood that these cams operate in pairs upon similar lifting rods on opposite sides of the machine, as clearly shown in Figs. 1 and 3, so that the punched plate will be raised evenly on both sides and at an incline from its front end to its rear end.

The anti-friction roller support provided

by the upper ends of the lifting rods permits the plate to be easily slid forwardly from the die bed 41 upon the rollers 74. From here it can be lifted by a crane or 5 other suitable conveying means and removed from the machine to permit another one to be inserted.

While I have described my invention as taking a particular form, it will be understood that the various parts of my invention may be changed without departing from the spirit thereof, and hence I do not limit myself to the precise construction set forth, but consider that I am at liberty to 10 make such changes and alterations as fairly come within the scope of the appended claims.

Having thus described my invention, what I claim as new and desire to secure by 20 Letters Patent is:

1. A punching machine including punching elements; a supporting bed; resiliently pressed means supporting the article to be punched, said means being supported on said 25 bed and located between said punching elements, whereby said article is maintained in a plane during the initial engagement of said article by the punching elements; and means for raising said plate above said bed; 30 substantially as described.

2. A punching machine including a bed for supporting articles to be punched; means for punching said articles; lifting means movable upwardly through the bed and 35 adapted to push the articles after they have been perforated due to the punching directly upward from the bed and hold them above the bed so as to permit the free removal thereof; substantially as described.

40 3. A punching machine including a bed for the article to be punched; means for punching said article; and lifting means for raising and holding said article at an incline and above said bed, whereby the 45 article can be freely removed from the machine; substantially as described.

4. A punching machine including a bed for the article to be punched; means for punching said article; and lifting means 50 for raising and holding said article at an incline and above said bed; said lifting means having anti-friction rollers thereon for engagement with said article, whereby

the article can be rolled off said lifting means and thereby freely removed from the 55 machine; substantially as described.

5. A punching machine including a bed for the article to be punched; means for punching said article; lifting rods; and cams operative upon said lifting rods to raise 60 them into engagement with said article to lift said article above said bed, whereby it can be freely removed from the machine; substantially as described.

6. A punching machine including a bed 65 for the article to be punched; means for punching said article; lifting rods; and cams operative upon said lifting rods to raise them into engagement with said article to lift said article above said bed; said 70 cams being operative to move said lifting rods to various extents, whereby said article will assume an inclined position above said bed so that it can be freely removed from the machine; substantially as described. 75

7. A punching machine including a bed for the article to be punched; means for punching said article; lifting rods; and cams operative upon said lifting rods to raise 80 them into engagement with said article to lift said article above said bed; said lifting rods having anti-friction rollers thereon for engagement with said plate, whereby the plate will be raised above said bed so that it can be freely removed from 85 the machine; substantially as described.

8. A punching machine including a bed for the article to be punched; means for punching said article; lifting rods; anti-friction rollers carried by said lifting rods; 90 and cams operative upon said lifting rods to raise them to cause said anti-friction rollers to engage said article; said cams being operative to move said lifting rods to various extents whereby said article will be raised 95 above said bed and at an incline so that the article can be freely rolled from the machine; substantially as described.

In testimony whereof I have signed my name to this specification in the presence of 100 two subscribing witnesses.

HARRY COHEN.
